UNITED STATES PATENT OFFICE

125,888

DESIGN FOR A COMBINED SOLE AND HEEL

Robert E. Frederick, New York, N. Y.

Application January 23, 1941, Serial No. 98,335

Term of patent 3½ years

To all whom it may concern:

Be it known that I, Robert E. Frederick, a citizen of the United States of America, residing in New York, county of New York, and State of New York, have invented a new, original, and ornamental Design for a Combined Sole and Heel, of which the following is a specification, reference being had to the accompanying drawing, forming part thereof.

Fig. 1 is a perspective view of a combined sole and heel showing my new design.

Fig. 2 is a side elevational view thereof.

I claim:

The ornamental design for a combined sole and heel, as shown.

ROBERT E. FREDERICK.
